US00D775088S

(12) **United States Design Patent** (10) **Patent No.:** **US D775,088 S**
Byrne et al. (45) **Date of Patent:** **** Dec. 27, 2016**

(54) **ELECTRICAL BUS BAR**

(71) Applicants: **Norman R. Byrne**, Ada, MI (US);
Robert L. Knapp, Rockford, MI (US);
Steven K. Meek, Grand Rapids, MI (US); **Matthew R. Andree**, Rockford, MI (US)

(72) Inventors: **Norman R. Byrne**, Ada, MI (US);
Robert L. Knapp, Rockford, MI (US);
Steven K. Meek, Grand Rapids, MI (US); **Matthew R. Andree**, Rockford, MI (US)

(**) Term: **15 Years**

(21) Appl. No.: **29/562,435**

(22) Filed: **Apr. 26, 2016**

(57) **CLAIM**

The ornamental design for an electrical bus bar, as shown and described.

DESCRIPTION

FIG. 1 is a rear and top perspective view thereof, shown in use condition.

FIG. 2 is a top perspective view thereof;

FIG. 3 is a top plan view thereof;

FIG. 4 is a bottom plan view thereof;

FIG. 5 is a front elevation thereof;

FIG. 6 is a rear elevation thereof;

FIG. 7 is a right side elevation thereof;

FIG. 8 is a left side elevation thereof; and,

FIG. 9 is a front perspective view of the electrical bus bar of FIG. 1, with environmental structure shown in an exploded view.

In the drawings, the broken lines depict unclaimed subject matter only and form no part of the claimed design.

1 Claim, 3 Drawing Sheets
